FREDERICK K. FISH, JR., OF SAN FRANCISCO, CALIFORNIA.

PROCESS AND APPARATUS FOR MAKING PULP FROM FIBROUS MATERIAL.

Application filed July 15, 1925. Serial No. 43,851.

This invention relates to improvements in process and apparatus for making pulp from fibrous material and more particularly relates to the circulation of the cooking liquor in the digester.

In methods now employed in cooking pulp, live steam is blown into the digester to cause circulation and to raise the temperature and pressure of the digesting liquor 10 to raise the temperature of the material, and increase the pressure in and around the material being cooked. The water of condensation from the steam dilutes the cooking liquor to a very great degree, particularly in 15 bringing the heat degree in the digester up through a relatively long range of temperature. Moreover the reduction in circulation, due to the decrease in the amount of steam entering the digester as the temperature and 20 pressure increase to the maximum required, and thereafter to the end of the cook, very materially delays the cook beyond the time that would be required if the rapid circulation first attained, could be maintained 25 throughout. When the digester becomes filled with liquor, it is necessary to remove liquor therefrom, in order that steam may be admitted to maintain the required temperature as the cook progresses. Furthermore, 30 owing to the reactions taking place between the cooking liquor and the encrusting substances of the fibrous material, the reactive properties of the liquor first penetrating the material, is quickly weakened 35 and thus the cooking is further retarded.

In the sulphite process, particularly, to prevent burning or discoloration of the fibrous material, and to prevent weakening of the fibre, too high a temperature must 40 be avoided, prior to the time at which the protective properties of the cooking liquor have been applied to the individual fibres.

In the sulphite process, while the temperature is being raised, and throughout the 45 cook, a considerable quantity of SO_2 gas is liberated from the sulphite liquor, and this, as well as, valuable extractives of the material under treatment, collect above the charge in the digester. In the blow-off as 50 practiced with digesters now in use, the gases intermixed with the extractives are removed and their values are lost, hence these substances do not exert their maximum cooking action on the material in the digester. These substances, essential and valuable in the cooking operation, are ordinary

ily removed from the digester through the relief line, and after cooling and separation, the SO_2 gas is returned to the liquor storage tank for use in a subsequent cook, thus losing the effect of large quantities of heat, which must necessarily be made up, as by the addition of steam. This fluid, so relieved, passes from the digester in the form of gas, or steam charged with gases and 60 extractives of the material under treatment, or as liquor, though in any shape they still possess valuable cooking properties.

In the present invention these fluids, possessing valuable digesting or cooking properties, are periodically removed from the space above the charge in the digester and are thereafter returned to the lower portion of the digester to enrich the contained liquor and for further effective use in the same 70 cook. As in other methods, the valuable extractive properties of these fluids have been utilized up to the point of their removal from the digester, but by their return to the lower portion of the digester and their reuse in the same cook, there is a very materially increased effect and added value of 75 my improved process as a result.

This invention thus provides a method of 80 reducing the time of the cook, wherein by periodically and suddenly reducing the pressure in the digester, what may, for convenience, be termed "explosions" occur and expel from the material being cooked, digesting liquor which has been weakened 85 within the material, as well as melted, dissolved or decomposed portions of encrusting substances of the material. A liquor of increased strength in these extractive material properties is then forced into the material being cooked, which, as a result of 90 the "explosions," is naturally more susceptible to impregnation by the liquor.

In the accompanying drawing an apparatus for operating the process is shown in 95 elevation and partly in section and my invention will be best understood by reference thereto.

In the drawing, 1 indicates a digester of the usual type, having a steam inlet 2 and a discharge outlet 3 at the bottom, and means 4 at the top for removing air from the material charged into the digester and reducing the pressure therein below atmospheric.

Located adjacent to the digester is a pressure tank 5 connected to the bottom part 100 of the digester by a pipe 6 having a valve

7. Connected with the bottom of the pressure tank and the space in the digester above the level of the charge and digesting liquor is a pipe 8 having valves 9 and 18. The 5 lower end of the pipe 8 is connected with the pipe 6 by means of the extension 19 having a valve 20 in order that the gases and vapors may be drawn directly from the upper part of the digester or from the upper 10 part of the tank. In like manner the bottom of the pressure tank is connected to the upper part of the digester, at a point below the level of the digesting liquor by a pipe 10 having valves 11, 11^a and the pipe 10 15 is extended to connect with the pipe 6 as shown, a valve 21 being provided in the extension of the pipe 10. This connection makes it possible to withdraw the liquor from the upper part of the digester and 20 return it directly to the lower part of the digester, or to the tank at will. This step is performed preferably in the latter stages of the cook when it is desirable to remove fluid from the space above the charge in 25 the digester directly into the tank 5 for use in a subsequent cook. The pressure tank is also connected at its upper end with the pipe 8 by means of pipe 12 having a valve 13. Pipes 14 having valves 15 communicate with the upper and lower ends of the pressure tank, to supply to or remove from the tank steam, gas or liquor. A pump 16 is inserted in the pipe 6 to assist in circulating the liquor and gases in the cooking operation. 30
- 35 The pressure or accumulator tank 5 is large enough to hold sufficient fluid, which when removed from the digester, permits the necessary sudden reduction of pressure in the digester before the pressure in the tank becomes equal to that in the digester. Air 40 is removed from this tank before fluid is admitted from the digester, suitable screens 17 are provided on the various pipes entering the digester to prevent admission thereto 45 of the fibrous material of the charge.
- 50 In carrying out the method, fibrous material is introduced into the digester, the valve in the means 4 is opened and air is removed from the digester and charge by means of a suction pump (not shown). Liquor is then introduced into the digester and the cook started.
- 55 After a temperature, say about 225° F. has been reached in the digester, an "explosion" within the fibrous material is caused by a sudden lowering of pressure in the digester which permits the formation of steam, thereby causing an outflow of more or less "spent" liquor from the fibrous material and necessarily permitting an inflow of a more effective liquor into such fibrous material. This explosion or sudden lowering of pressure is effected by opening the valves 9 and 18 to permit the fluid in the form of gases and steam from the space in the upper portion

of the digester to rush into the pressure tank 5. Moreover the valves 11 and 11^a are opened to cause liquor from the charge to flow into the tank, both gases and liquor, entering the tank at its lower end preferably in such a way as to mix the gases and liquor. The valves 9, 11 and 11^a, are closed and the valve 7 opened, when the liquor enriched in the tank with the gases and volatile extractives are delivered to the lower part of the digester. This circulation is effected by means of the pump 16, and, if desired, may be assisted by admitting steam under pressure into the upper part of the tank 5 through the connection 14. Moreover before the valve 7 is opened steam may be admitted into the lower part of the tank 5 to thoroughly agitate and heat the mixture of liquor and gases and to increase the pressure therein. As the cook progresses the temperature 85 and pressure in the digester are raised to that required for effective cooking and the liquor uniformly strengthened is circulated through the whole body of liquor and charge in the digester. 90

This sudden release of pressure in the digester is carried out periodically and each successive "explosion" opens up the structure of the material under treatment and separates individual fibres and removes melted, dissolved and decomposed substances from within the fibrous material thus making it possible to more easily reach and act upon the individual fibres and to force a greater amount of liquor into intimate contact with the material. 100

The fluid withdrawn during the latter part of the cook from the top of the digester may be stored in the tank 5 for use in a succeeding cook. To effect this valves 7, 9, and 11 are 105 closed and valves 13 and 18 opened to permit the gases to flow into the upper portion of the tank.

In the early stages of the cook I have found it advantageous to remove liquor from the lower part of the digester, where the temperature is highest and the liquor weakened by the steam admitted, into the tank and force it to the top of the digester to produce uniformity of concentration and temperature, and circulation throughout the charge as promptly as possible. 110

This is effected by opening valves 21 and 11^a to permit liquor from the lower part of the digester to flow into the tank 5. Valves 21 and 11 are then closed, valves 9 and 18 opened and steam admitted to the upper part of the tank 5 to force the liquor to the top of the digester for the purpose described. 115

It will be apparent that I may conduct the operation at any desired suitable temperature and pressure and that there will be no condensation of the gases and vapors removed from the digester to the accumulator tank. 120 125 130

While I have described my invention in detail it will be understood that various changes may be made in the operation thereof without departing from the spirit of the invention, the scope of which is defined in the following claims.

What I claim is:—

1. The process of making pulp from fibrous material, consisting in removing air from the fibrous material to reduce the pressure therein below atmospheric, then digesting said fibrous material in digesting liquor highly heated and under pressure and with a space above the body of liquor, suddenly reducing the pressure correspondingly in said space and in the liquor and directing the fluid flowing as a result of such pressure reduction into a closed tank, raising the temperature of the fluid in the tank and thereafter reintroducing the fluid from the tank into the digesting liquor to mix with said liquor for further use in the same cook.

2. The process of making pulp from fibrous material consisting in removing air from the fibrous material to reduce the pressure therein below atmospheric, then cooking said fibrous material in digesting liquor highly heated and under pressure, and with a space above the body of liquor, suddenly reducing the pressure correspondingly in said space and in the liquor, and directing only the fluid flowing as a result of such pressure reduction into a closed tank, from which air has been removed, and thereafter reintroducing the fluid to the bottom of the digesting liquor to mix with said liquor for further use in the same cook.

3. The process of making pulp from fibrous material consisting in removing air from the fibrous material to reduce the pressure therein below atmospheric, then submerging said fibrous material in heated digesting liquor under pressure in a digester, periodically regulating the temperature and pressure of the digesting liquor to cause gas or liquor within the fibrous material to suddenly expand and thereby cause a separation of the fibres, recovering the fluid which alone escapes from the digester as a result of the control of the temperature and pressure, and thereafter introducing the recovered fluid into the digester.

4. The process of making pulp from fibrous material consisting in removing air from the fibrous material to reduce the pressure therein below atmospheric, then submerging said fibrous material in and subjecting it to highly heated digesting liquor under pressure, suddenly reducing the pressure and temperature of the digesting liquor surrounding the fibrous material to cause an outflow of the liquor from the fibrous material, thereby separating the fibres, recovering the fluid exclusively emitted by the sudden release of pressure and temperature,

and thereafter introducing the recovered fluid to the digesting liquor in the same cook to enrich the liquor to be forced into the cells when the temperature and pressure in the digester are again increased.

70

5. The method of making pulp from fibrous material consisting in removing air from the fibrous material to reduce the pressure therein below atmospheric, then subjecting said fibrous material to digesting liquor highly heated and under pressure, suddenly reducing the pressure in the digester and recovering the fluid exclusively emitted therefrom in a closed tank and thereafter forcing the fluid from the tank into the lower part of the body of the liquor in the digester to cause a circulation of the liquor in the digester.

75

6. The process of making pulp from fibrous material consisting in removing air from the fibrous material to reduce the pressure therein below atmospheric, then subjecting said fibrous material to a heat digesting liquor under pressure, periodically reducing the pressure and temperature of the liquor surrounding the fibrous material and recovering the fluid exclusively released by such reduction of pressure and temperature, and thereafter introducing said recovered fluid to the digesting liquor for use in the same cook.

85

7. The process of making pulp from fibrous material consisting in removing air from the fibrous material to reduce the pressure therein below atmospheric, then cooking said fibrous material in a heated digesting liquor in a digester, removing fluid from the digester above the material being cooked into a tank, and thereafter raising the temperature of the fluid so removed and returning it to the digester for re-use in the same cook.

90

8. The process of making pulp from fibrous material consisting in removing air from the fibrous material to reduce the pressure therein below atmospheric, then subjecting said fibrous material to highly heated digesting liquor under pressure, circulating the liquor and gases from the upper portion of the digester through a pressure tank, raising the temperature of said liquor in said pressure tank and then introducing said liquor from the tank to the body of liquor in the digester near its bottom, to thereby cause circulation of the liquor in the digester and assist in maintaining the temperature and pressure therein.

100

9. The process of making pulp from fibrous material, consisting in removing air from the fibrous material to reduce the pressure therein below atmospheric, then submerging said fibrous material in heated digesting liquor under pressure, controlling the temperature and pressure to suddenly cause liquor within the fibre to expand into steam

110

115

120

125

130

- and separate the fibres, recovering the fluid which is alone permitted to escape from the digester as a result of the control of the temperature and pressure, and thereafter reintroducing the recovered fluid into the digester.
10. The process of making pulp from fibrous material, consisting in removing air from the fibrous material to reduce the pressure therein below atmospheric, then subjecting said fibrous material to heated digesting liquor under pressure, periodically reducing the pressure and temperature to cause a successive series of explosions within the fibrous material, to thereby cause an outflow from the fibrous material of weakened liquor containing decomposed or dissolved portions of the fibrous material, recovering the fluid so released and reintroducing it into the digesting liquor to cause an inflow of stronger liquor into the cells of the said fibrous material in the same cook.
11. The process of making pulp from fibrous material, consisting in digesting said fibrous material in digesting liquor highly heated and under pressure, and with a space above the body of liquor, suddenly reducing the pressure correspondingly in said space and in the liquor by releasing fluid from the space above the body of liquor, and directing the fluid flowing as a result of such pressure reduction into a closed tank from which the air has been removed, and thereafter reintroducing the fluid to the bottom of the digesting liquor to mix said fluid with said liquor for further use in the same cook.
12. The process of making pulp from fibrous material consisting in submerging said fibrous material in heated digesting liquor under pressure, periodically regulating the temperature and pressure of the digesting liquor to cause liquor within the fibre to periodically and suddenly expand into steam and separate the fibers, recovering the fluid which is alone permitted to escape from the digester as a result of the control of the temperature and pressure, and thereafter reintroducing the recovered fluid into the digester.
13. The process of making pulp from fibrous material consisting in subjecting fibrous material to a heated digesting liquor in a digester, removing gases, vapors, and liquor from the upper portion of the digester into a tank, mixing the said gases, vapors and liquor in said tank and returning the mixture to the lower portion of the digester for re-use in the same cook.
14. The process of making pulp from fibrous material, consisting in digesting said fibrous material in digesting liquor highly heated and under pressure, and with a space above the body of liquor, suddenly reducing the pressure correspondingly in said space and in the liquor by releasing fluid from said space and directing the fluid flowing as a result of such pressure reduction into a closed tank, raising the temperature of the fluid in the tank above that of the liquor in the digester and thereafter introducing the fluid from the tank into the digesting liquor to mix such released fluid with said liquor for further use in the same cook.
15. The process of making pulp from fibrous material, consisting in subjecting said fibrous material to a heated digesting liquor under pressure, periodically suddenly reducing the pressure and temperature of the liquor surrounding the fibrous material and recovering the fluid released by such reduction of pressure and temperature, and thereafter introducing said recovered fluid without separation to the lower portion of the column of digesting liquor for use in the same cook.
16. The process of making pulp from fibrous material consisting in subjecting said fibrous material to heated digesting liquor under pressure in a digester, periodically reducing the pressure and temperature of the liquor surrounding the fibrous material to cause a successive series of explosions within the fibrous material, thereby causing an outflow from the fibrous material of weakened liquor, containing dissolved and decomposed portions of the fibrous material, recovering said fluid, raising its temperature and reintroducing it to the lower portion of the digester.
17. The method of making pulp from fibrous material, consisting in subjecting said fibrous material to digesting liquor highly heated and under pressure, suddenly reducing the pressure in the digester and recovering the fluid exclusively emitted therefrom in a closed tank, and thereafter forcing the fluid from the tank into the lower part of the body of the liquor in the digester to cause a circulation of the liquor in the digester.
18. The process of making pulp from fibrous material, consisting in subjecting said fibrous material to digesting liquor under pressure and temperature above the normal boiling point of the liquor, suddenly reducing the temperature and pressure of the liquor surrounding the substance by releasing gases and liquor from the upper portion of the digester to remove by force from the fibrous substance dissolved and decomposed portions of the fibrous substance, recovering and mixing the fluids so released, and thereafter reintroducing the mixed fluid so recovered into the body of the digesting liquor to recharge the same and cause said fluid to circulate through the liquor in the same cook.
19. The process of making pulp from fibrous material, consisting in subjecting said fibrous material to heated digesting liquor under pressure, suddenly reducing the

- pressure of the liquor surrounding the substances by releasing liquor from the digester, to remove by force from the fibrous substance, dissolved and decomposed portions of the fibrous substance, recovering the liquor so exclusively released, and thereafter reintroducing the liquor so recovered into the body of the digesting liquor for further use in the same cook.
- 10 20. The process of making pulp from fibrous material, consisting in cooking said fibrous material in digesting liquor under pressure, in a digester, suddenly reducing the pressure of the digesting liquor to or about that of the atmosphere by releasing fluid from above the body of liquor in the digester and recovering said fluid, then cooking the fibrous substance at or about atmospheric pressure and thereafter reintroducing the recovered fluid into the body of digesting liquor to recharge the latter and cause circulation of said fluid through said liquor in the same cook.
- 15 21. The process of making pulp from fibrous material, consisting in cooking said fibrous material in digesting liquor which is enriched and heated during the cook by introducing thereto liquor containing valuable gases and other digestive extractives which have risen above the fibrous material being cooked and which have been periodically separated from the digesting liquor and subjected to a mixing without permitting condensation or separation of such gases before being reintroduced to the digesting liquor.
- 20 22. An apparatus for making pulp which comprises a digester, a pressure tank adjacent the digester, means to remove fluid and liquor separately from the upper portion of the said digester and transfer them to the said tank, and means to circulate the said removed fluid and liquor from the tank to the digester.
- 25 23. An apparatus for making pulp comprising a digester, a tank, a pipe adapted to communicate with the upper and lower portions of the said tank and the space above the liquor level in said digester, and a pipe connecting the lower portion of said tank with the upper portion of the digester at a point below the liquor level therein, said pipes having extensions connected with a further pipe line connecting the bottom of said tank with the lower portion of the digester.
24. An apparatus as defined in claim 23 having means for removing air from the said digester, and valves arranged to permit a circulation and mixing of the gases, vapors and liquor in the digester.
25. An apparatus as defined in claim 23 wherein the said extensions are so connected with the said pipe line as to cause intimate mixture of gases, vapors and liquor in transit between the upper and lower portions of the digester.
26. An apparatus for making pulp comprising a digester, a pressure tank adjacent said digester, a pipe connecting the lower portion of the digester with said tank, a second pipe connecting the lower portion of the tank with the upper portion of the digester and means to force liquor from the lower portion of the said tank to the upper portion of the digester.
27. An apparatus for making pulp comprising a digester, a pipe connecting a pump with the lower portion of the digester, a pipe connecting the intake of said pump with the upper portion of the digester at a point below the liquor level therein and a further pipe connecting the space above the liquor in the digester with the said intake pipe and adapted for the withdrawal and mixing of liquor, gases and vapors from the upper portion of the digester and for returning them to the lower portion of the said digester.
28. The process of making pulp from fibrous material consisting in subjecting the fibrous material in a digester to heated digesting liquor with a space above the body of liquor, removing liquor from the upper portion of the digester and returning it directly to the lower part of the digester, while relieving fluid from the space above the liquor into an accumulator tank for use without separation in a subsequent cook.
29. The process of making pulp from fibrous material consisting in cooking said fibrous material in digesting liquor which is enriched and heated during the cook by introducing liquor containing valuable gases and other digestive extractives which have risen above the fibrous material being cooked and are ordinarily permanently removed from the digester, without permitting condensation or separation of the said gases.

In testimony whereof I affix my signature.

FREDERICK K. FISH, JR.
